Patented Apr. 22, 1919.

By Watson E. Coleman
Attorney

UNITED STATES PATENT OFFICE.

JOHN SOVICK, OF CLAIRTON, PENNSYLVANIA.

RAIL-JOINT.

1,301,615.

Specification of Letters Patent. Patented Apr. 22, 1919.

Application filed November 1, 1918. Serial No. 260,720.

To all whom it may concern:

Be it known that I, JOHN SOVICK, a citizen of the United States, residing at Clairton, in the county of Allegheny and State of Pennsylvania, have invented certain new and useful Improvements in Rail-Joints, of which the following is a specification, reference being had to the accompanying drawings.

This invention relates to certain improvements in rail joints, and it is an object of the invention to provide a novel and improved joint of this general character comprising a base plate and splice bars coacting with the meeting ends of the rails, and whereby the same are effectively maintained in assembled relation without the use of bolts or other fastening members associated with the splice bars and the web of the rails.

The invention consists in the details of construction and in the combination and arrangement of the several parts of my improved rail joint whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation illustrating a rail joint constructed in accordance with an embodiment of my invention;

Fig. 2 is a sectional view taken substantially on the line 2—2 of Fig. 1; and

Fig. 3 is a sectional view taken substantially on the line 3—3 of Fig. 1.

As disclosed in the accompanying drawings, T denotes adjacent ties having resting upon the upper faces thereof the metallic plates P. The meeting ends of the rails are positioned upon the plates P and maintained in assembled relation through the medium of the splice bars B arranged at opposite sides thereof. Each of the bars B comprises an elongated plate 1 adapted to engage the web between a base flange F and a head H of each of the rails R and with a bottom flange 2 adapted to rest upon the base flange F. Each end of the bar B or more particularly the bottom flange 2 is provided with outwardly directed extensions or lugs 3 provided at adjacent end portions with open-

ings 4 through which the spikes S are adapted to be driven.

The portion of each of the flanges 2 between the extensions or lugs 3 is provided with an inwardly directed flange 5 which is adapted to underlie the meeting ends of the rails and whereby the bar is effectively held in applied position.

In applying the bars B the spikes S are first disposed through the outer openings 4 of the extensions or lugs 3 which results in the bars being pulled down to the plates P with the upper portion of each of the bars slightly spaced from the rails R. The additional spikes S are then applied through the inner openings 4 which results in the bars B being further pulled down and properly coacting with the meeting ends of the rails.

It is to be understood that each of the plates P is provided with openings 7 with which the openings 4 register when the bars B are in applied position. It is also preferred that each of the plates P be provided with the upstanding ribs or abutments 6 with which the outer or free ends of the extensions or lugs 4 engage so that the bars B are prevented from having movement in a direction away from the meeting ends of the rails when the spikes S are being set.

As illustrated in the accompanying drawings, the bars B are slightly spaced from the under surfaces of the heads of the rails R. This is done because it often occurs in practice that the rails R or more particularly the webs thereof slightly differ in height.

I also find it desirable to have the upper and lower marginal portions of each of the bars B provided with the inwardly directed ribs or beads 7' having their contacting surfaces rounded so that the application or removal of the bars B may be materially facilitated.

From the foregoing description it is thought to be obvious that a rail joint constructed in accordance with my improved invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein

shown in carrying out my invention in practice except as hereinafter claimed.

I claim:—

In combination with the meeting ends of 5 rails, splice bars engaging opposite sides thereof between the heads and flanges of the rails, the upper marginal portions of the bars being spaced from and in close proximity to the under surfaces of the heads of the 10 rails, the upper and lower marginal portions of the bars being provided with inwardly directed beads having their contacting surfaces rounded, each of said bars adjacent its opposite ends being provided with

outwardly directed extensions, each of said 15 extensions having spike openings adjacent its opposite ends, plates extending beneath the rails and adapted to rest upon supporting ties, said plates being provided with openings with which the openings in the extensions of the bars register, said plates being provided with upstanding abutments with which the outer ends of the extensions of the bar engage.

In testimony whereof I hereunto affix my 25 signature.

JOHN SOVICK.
